UNITED STATES PATENT OFFICE.

KALLE JARVI AND KARL MAKINEN, OF ISHPEMING, MICHIGAN.

RAILWAY APPLIANCE.

1,206,712.

Specification of Letters Patent. Patented Nov. 28, 1916.

Application filed May 4, 1916. Serial No. 95,405.

To all whom it may concern:

Be it known that we, KALLE JARVI and KARL MAKINEN, citizens of the United States of America, and residents of Ishpeming, in the county of Marquette and State of Michigan, have invented certain new and useful Improvements in Railway Appliances, of which the following is a specification.

10 This invention relates to railways and particularly to cross ties and rail fastenings.

An object of this invention is to produce a novel cross tie, associated with means for anchoring rails through the said device embodying novel means whereby the said rails are clamped to the cross ties when the sections of the cross tie are assembled and secured together.

20 A further object of this invention is to provide novel means whereby the clamping members are automatically operated when the sections of the cross tie are assembled, means being furthermore provided for automatically securing the sections of the rail 25 together when the said sections are nested in proper relation to each other.

With the foregoing and other objects in view, the invention consists in the details of construction, and in the arrangement and 30 combination of parts to be hereinafter more fully set forth and claimed.

In describing the invention in detail, reference will be had to the accompanying drawings forming part of this specification 35 wherein like characters denote corresponding parts in the several views, and in which—

Figure 1 illustrates a view in perspective of sections of a cross tie with parts embodying the invention associated therewith; Fig. 40 Fig. 2 illustrates a longitudinal sectional view of the cross tie when the parts are assembled; Fig. 3 illustrates a sectional view on a line corresponding with the line 3—3 of Fig. 2; and Fig. 4 illustrates a perspective view of a fragment of a cross tie, embodying a slight modification.

In these drawings 5 denotes the base of the cross tie, and 6 the top which fits over 50 the sides and ends of the base. The base consists of a bottom portion 7 with side flanges 8 whereas the top has side flanges 9 and end flanges 10, and the said top covers the base and protects the interior mechanism from access of foreign substances.

55 The upper surface of the cover or top has

lugs 11 struck therefrom and bent upwardly to overlie one of the base flanges of a rail 12, the other base flange of each rail being secured by a movable clamp 13 which projects through an aperture 14 in the cover, it being understood that one of these clamps is provided for each rail and that one of such clamps co-operates with one of the lugs 11 for anchoring the rail to the cross 60 tie. Each clamp 13 has a tail piece 15 which curves downwardly and longitudinally of the cross tie, said tail portion being of such length as to engage the base when the cover is applied thereto, and these tail 70 pieces are preferably slightly resilient so that they maintain pressure which causes the clamps to firmly engage and hold the rails.

When the cover is applied to the base of 75 the cross tie, these parts are automatically secured together by means of a latch 16 with a shoulder 17 overlying the upper surface of the cover. The latch projects through an aperture 18 in the said cover 80 and the said latch is anchored to the base by reason of the fact that the member constituting the latch has an angularly disposed portion 19 lying on the upper surface of the base and being secured thereto by 85 fastenings such as rivets 20, although the exact form of the means for anchoring the latch to the base is immaterial.

From an inspection of Figs. 1, 2 and 3, it will be apparent that when the cover is 90 applied to the base, when the flanges of the rail are interposed between the lugs and clamps, movement of the cover with relation to the base causes an impact of the tail pieces of the clamps with the base of the 95 cross tie, thus causing a pressure of the clamps on the base flanges of the rails and this pressure is maintained so long as the cover and base are in assembled relation. It will be furthermore understood that 100 when the cover is applied to the base, the latch projects through the aperture of the cover and engages the upper surface of the cover for retaining the parts in the assembled relation stated.

105 Instead of having the cover supplied with an integral clamping member or lug, the said means may be modified by providing a cover such as A and having the clamp B secured to it by screws or bolts such as C, 110 it being understood that this clamping member is adapted to engage the base flange

of the rail and to coact with the other clamps, such as 13 for holding the rail in place.

We claim

- 5 1. In a cross tie, a base, a cover having an aperture in its top applied to the said base, lugs struck from the said cover and constituting rail engaging members, said cover having apertures adjacent the rail engaging members, clamps extending through the apertures and engaging the rail, tail pieces on the said clamps bearing against the base for exerting pressure of the clamps on the rail, and a latch secured to the base 10 and projecting through an aperture of the cover for retaining the said cover in place.
- 15 2. In a railway appliance, a base, a cover embracing the base, said cover having apertures therein, rail engaging lugs struck from the said cover and adapted to engage the 20

base flanges of the rails, movable clamps extending through apertures of the said cover, tail pieces on the said clamps extending downwardly and longitudinally of the cross tie, the parts being in such relation 25 that when the cover is seated on the base the tail pieces are in engagement with the said base and cause pressure to be exerted by the clamps of which they are a part, and means for holding the sections of the cross 30 tie in assembled relation to each other.

In testimony whereof, we hereunto affix our signatures in the presence of two witnesses.

KALLE JARVI.
KARL MAKINEN.
